UNITED STATES PATENT OFFICE.

WILLIAM F. GARLAND, OF NEW YORK, N. Y.

CARRYING DRUM OR REEL.

1,390,286.

Specification of Letters Patent. Patented Sept. 13, 1921.

Original application filed December 31, 1912, Serial No. 739,463. Divided and this application filed December 16, 1918. Serial No. 266,866.

To all whom it may concern:

Be it known that I, WILLIAM F. GARLAND, a citizen of the United States, residing at New York city, in the county of New York and State of New York, have invented certain new and useful Improvements in Carrying Drums or Reels, fully described and represented in the following specification and the accompanying drawings, forming a part of the same.

This invention relates to carrying reels or drums intended especially for use in developing photographic films, the film being wound on the drum to be subjected to the action of developing, fixing and washing liquids and thereafter dried, usually while still on the drum.

The invention aims to provide a film carrier adapted to take up slack in the film resulting from expansion of the film when wet, and to yield to permit the film to contract in drying, thereby maintaining the film in position and held flat and under proper tension at all times after it is placed on the carrier. Some considerable difficulty has been experienced heretofore in the development of long moving picture films due to the fact that when the film becomes wet after being wound around the usual carrying reel or drum it expands and becomes loose and is liable to move out of place or not to be held stretched out flat on the drum. This has made it necessary for best results to readjust the film on the drum to take up the slack after the film has been wet and then to loosen or again readjust the film before or during drying to prevent its being subjected to too great a tension, whereby it might be warped and distorted. By my invention I avoid this difficulty by providing a carrying reel or drum with means, preferably automatic in action, whereby slack in the film due to expansion when it is wet is taken up, and whereby the film is allowed to contract without undue increase of tension thereon as it dries.

As a full understanding of the invention can best be given by a detail description of a construction embodying the features of the invention in a preferred form, such a description will now be given in connection with the accompanying drawings showing

part of a developing machine which is more fully shown and described in my original application, Serial No. 739,463, filed December 31, 1912, (upon which Patent No. 1,288,403 has been issued,) of which this application is a division, such machine as disclosed in said original application and as shown in the accompanying drawings being provided with a film-carrying reel or drum made in accordance with the invention herein claimed. In said drawings:—

Figure 1 is a sectional view of the developing chamber of said machine.

Fig. 2 is a view partly in front elevation and partly in section on line 2—2 of Fig. 1; and

Fig. 3 is a detail view.

Referring to the drawings, with the apparatus shown the developing, fixing and washing of the film is accomplished within a light-tight cylindrical casing 10, the lower part of which forms a tank for holding the developing, fixing and washing liquids during the time that the film is to be subjected to the action of such liquids, and for holding other liquids to the action of which it may be desired to subject the film. Mounted to rotate within the casing is a skeleton drum 80 or reel for carrying the film. The drum is removably supported within the casing by means of brackets 13 extending from the end walls of the casing and formed to provide bearings for the end trunnions 14 of the drum. For removing the carrier drum from and placing it within the casing, the casing is formed with an opening at one side which is normally closed by a door 15. The drum, as shown, is rotated by means of a hand crank 16 adapted to have its shaft end placed through an opening in one of the end walls of the casing and in operating engagement with the end of one of the drum trunnions 14. When the drum is to be removed the crank will be pulled out of engagement with the drum trunnion. Obviously, power operated driving connections may be provided for rotating the drum, or other suitable means provided for manually rotating the drum.

The carrying drum or reel may be of any suitable construction, but to provide a light, strong drum which may be easily handled,

I preferably make the drum of the construction shown having no axial shaft, but having end disks or hubs 17 which carry the shaft trunnions 14 and from which extend 5 radial arms 18 set into radial sockets in the hubs or extensions from the hubs, as shown, and which carry at their outer ends the tie rods or peripheral supports 19. The films to be developed will be secured to and supported by the longitudinal rods 19, and long 10 moving picture films will be wound spirally about the drum on these rods. The film may be attached to the drum while it is in the machine or may be wound on the drum 15 by means of a suitable winding apparatus while the drum is removed from the machine and the loaded drum then placed in position within the casing 10.

The films will usually be wound on to the 20 drum while dry. The wetting of the films causes them to expand, so that with a drum such as heretofore used the film becomes loose and liable to become displaced, and to avoid this it has been customary heretofore 25 to readjust the film to take up this slack. To avoid this difficulty, I provide the drum as before stated with means for taking up such slack and for allowing the film to contract again on drying. For this purpose, I 30 provide the drum with one or more longitudinally extending film supports movable radially outward and inward to take up slack in the film or to allow the film to contract, and such supports are preferably 35 spring-pressed so as to move automatically outward as the film expands and inward as the film contracts. In the preferred construction shown, each alternate supporting rod 19 is pivotally mounted on its radial 40 arms 18 and extends from its pivotal axis in a direction circumferentially of the arm, so that it may swing on its pivots in a direction substantially radial of the drum, and is spring-pressed outward by springs 45 20. These spring-pressed take-up rods or bars 19, which are also designated by the reference letter *a*, are conveniently made of flat strips, as shown, of wood or other suitable material, and are limited in their inward movement by stops 21, so that when the film is being wound dry on the drum the take-up rods will be held in their innermost position so that the film may be wound under even tension. Obviously, a lesser 50 55 number or a greater number or even all of the supporting rods 19 might be formed so as to operate as automatic take-up rods.

The developing, fixing and washing liquids are supplied as desired to the tank 60 11 formed by the lower portion of the casing 10 through a pipe 28, and the tank 11 is emptied through a discharge pipe 29. Beneath the tank 11 is a closed tank 40 which may be supplied with cold or heated liquid 65 for cooling the liquid in the tank 11 or for

heating the developing chamber during the drying of developed and fixed films. The water in the tank 40 may be heated by means of a gas burner 50, or by other suitable means.

After the film applied to the drum has been developed, fixed and washed as fully explained in my said original application, it may be removed from the developing chamber for drying either by taking out the carrying reel with the film on it, or by unwinding the film from the reel on to some other support, or the film may be dried on the reel in the developing chamber. When drying within the chamber, the heating means is 70 desirably used to heat the air in the chamber, and for further expediting the drying, the apparatus may be provided with means for causing a movement of air through the developing chamber as from an inlet opening 55 at one end of the casing 10 to an outlet opening 56 at the other end of the casing, and the air may be caused to move through the casing by providing the radial arms 18 at one end of the carrying drum with inclined fan blades 57, as described and claimed in my said original application.

It is to be understood that the invention is not to be limited to the exact construction and arrangement of parts as shown in the 95 drawings, but that it includes changes and modifications thereof within the claims. It will be understood also that the invention claimed is not limited in its use to a developing machine as in the construction shown. 100

The word "film" as used herein is intended to include not only the transparent sheets of coated celluloid or other substance to which the term is usually applied, but also to include sheets or strips of paper, or other 105 flexible material.

What is claimed is:

1. A carrier drum for supporting photographic films during development provided with one or more hinged longitudinal 110 flanges, and means for turning the said flanges upon their hinges so as to press outwardly against a film wound upon the drum.

2. A carrier drum for supporting photographic films during development provided with one or more hinged flanges, resilient 115 means for tilting said flanges outwardly, and stops for limiting the inward movement of said flanges.

3. A carrier drum for supporting photographic films during development provided with one or more hinged flanges, resilient means for tilting said flanges outwardly, and stops adapted to arrest inward movement of said flanges when they reach a substantially tangential position.

4. A carrier drum for supporting photographic films during development having a plurality of longitudinally extending film supports spaced about the periphery of the 130

drum, resilient means for pressing said supports outwardly, and stops for limiting the inward movement of said supports.

5. A carrier drum for supporting photographic films during development provided with radially movable longitudinal film supports spaced about said drum, stops to limit the inward movement of said supports, and means for exerting an outward pressure upon said supports which will cause them to move outwardly in case of an expansion of

a film wound upon the drum but which will permit the supports to be pressed against the stops when a film is wound upon the drum.

In testimony whereof, I have hereunto set my hand, in the presence of two subscribing witnesses.

WILLIAM F. GARLAND.
